DESIGN FOR A DOLL

Barbara J. Donahue, Kalamazoo, Mich.

Application March 16, 1944, Serial No. 112,918

Term of patent 7 years

(Cl. D34—4)

To all whom it may concern:

Be it known that I, Barbara J. Donahue, a citizen of the United States, residing at the city and county of Kalamazoo, State of Michigan, have invented a new, original, and ornamental Design for Doll, of which the following is a specification, reference being had to the accompanying drawing, forming part thereof, in which:

Fig. 1 is a front view of a doll, showing my new design;

Fig. 2 is a side view; and

Fig. 3 is a rear view thereof, portions of the legs being broken away for convenience of illustration.

I claim:

The ornamental design for a doll, as shown.

BARBARA J. DONAHUE.
